(57) **CLAIM**

The ornamental design for a patient interface for corneal surgery, as shown.

DESCRIPTION

FIG. 1 is a top plan view of the patient interface for corneal surgery of the present invention;

FIG. 2 is a side elevation view thereof;

FIG. 3 is a bottom view thereof;

FIG. 4 is a top perspective view thereof;

FIG. 5 is a bottom perspective view thereof; and,

FIG. 6 is a cross-section view thereof as seen along the line 6—6 in FIG. 1.
